[57] **CLAIM**

The ornamental design for a wine bottle sealer, as shown and described.

DESCRIPTION

FIG. 1 is a left side, front and top isometric view of a wine bottle sealer, showing my new design, and shown without the sealing unit for completeness of illustration;

FIG. 2 is a top plan view thereof;

FIG. 3 is a front, elevational view thereof;

FIG. 4 is a right side elevational view thereof;

FIG. 5 is a rear elevational view thereof;

FIG. 6 is a bottom plan view thereof;

FIG. 7 is a left side, front and top isometric view of a wine bottle sealer, showing my new design in an extended orientation, and with a sealing unit at the bottom thereof;

FIG. 8 is a left side, front and top isometric view of a sealing unit, as shown in FIG. 7, but shown separately for completeness of illustration;

FIG. 9 is a top plan view of said sealing unit;

FIG. 10 is a front, elevational view of said sealing unit; and,

FIG. 11 is a bottom plan view of said sealing unit.
